ABSTRACT

A pair of dies are provided of which die faces are formed with depressions sequentially brought into engagement with a particular portion of a workpiece as the workpiece rolls between the die faces. By compressing the workpiece while driving the same to roll between the die faces, an excess metal of the workpiece is caused to flow into the depressions sequentially for thereby forming an asymmetrical part of the article.

METHOD OF FORMING ASYMMETRICAL ARTICLES BY ROLLING

This application is a continuation of application Ser. No. 07,289,052, filed Dec. 23, 1988, now abandoned, which is a divisional of Ser. No. 07/302,209, now abandoned, which is a divisional of Ser. No. 07/032,109, filed Mar. 30, 1987, now U.S. Pat. No. 4,811,585, issued Mar. 14, 1989.

BACKGROUND OF THE INVENTION

1. Field of the Invention

The present invention relates in general to rolling by using two or three cylindrical dies or a pair of flat or straight dies and more particularly to a method of and device for forming an asymmetrical article such as a shaft having a radial projection or an eccentric shaft section by rolling.

2. Description of the Prior Art

A rolling process has been widely used in production of metal articles such as stepped shafts since no stock is wasted in rolling the articles and the rolled product is superior in strength to the cut product. However, asymmetrical articles such as a shaft having a radial projection or an eccentric shaft section cannot be formed by the prior art rolling process.

For this reason, in production of some asymmetrical articles, a forging process for forming an intermediate product into a finished shape has been indispensable in addition to a rolling process for forming a workpiece into the intermediate product.

SUMMARY OF THE INVENTION

In accordance with the present invention, there is provided a method of forming an asymmetrical article by rolling, which comprises preparing a plurality of dies of which die faces are formed with independent patterns sequentially brought into engagement with a particular portion of a workpiece as the workpiece rolls between the die faces, and compressing the workpiece while driving the same to roll between the die faces and forming the particular portion of the workpiece into an asymmetrical portion of the article by the effect of the patterns of the die faces.

In accordance with the present invention, there is also provided a device for forming an asymmetrical article by rolling, which comprises a plurality of dies of which die faces are formed with independent patterns sequentially brought into engagement with a particular portion of a workpiece for thereby forming an asymmetrical part of the workpiece at the particular portion.

The above method and device make it possible to form an asymmetrical article by rolling.

It is accordingly an object of the present invention to provide a method of forming an asymmetrical article by rolling.

It is a further object of the present invention to provide a device for forming an asymmetrical article by rolling.

It is a further object of the present invention to provide a method of forming a crankshaft, which can reduce the manufacturing expense.

BRIEF DESCRIPTION OF THE DRAWINGS

FIG. 1 is a side elevational view of a pair of cylindrical dies according to an embodiment of the present invention;

FIG. 2A is a developed view of the die face of one of the cylindrical dies of FIG. 1;

FIG. 2B is a sectional view taken along the line 2B—2B of FIG. 2A;

FIG. 2C is an elevational view of variously shaped workpieces obtained at each stages a—a, b—b, c—c, d—d of FIG. 2B;

FIG. 2D is a side view of the workpieces of FIG. 2C;

FIG. 3A-3E are schematic views for showing how a workpiece is formed into an asymmetrical article by using the dies of FIG. 1;

FIGS. 4 and 5 show variants of the die face depressions of FIG. 1;

FIG. 6 is a schematic view of a pair of flat dies which can be used in place of the cylindrical dies of FIG. 1;

FIG. 7 is an elevational view of an asymmetrical article to be rolled by the dies of FIG. 1;

FIG. 8 is a side view of the article of FIG. 7;

FIGS. 9A-9D are schematic views of a method of forming a crankshaft according to another embodiment of the present invention;

FIG. 10 is a fragmentary side view of a pair of cylindrical dies for rolling the asymmetrical product of FIG. 9B;

FIG. 11 is an elevational view of the dies of FIG. 10;

FIG. 12 is a developed view of one of the dies of FIG. 10;

FIGS. 13A-13D are sectional views taken along the line a—a, b—b, c—c, d—d of FIG. 12;

FIG. 14 is a side view of a pair of cylindrical dies according to a further embodiment of the present invention;

FIG. 15 is an enlarged fragmentary view of the dies of FIG. 14;

FIG. 16A is a developed view of the die face of one of the dies of FIG. 14;

FIG. 16B is a sectional view taken along the line 16B—16B of FIG. 16A;

FIG. 16C is an elevational view of variously shaped workpieces obtained at each stages a—a, b—b, c—c, d—d of FIG. 16B;

FIG. 16D is a side view of the workpieces of FIG. 16C;

FIG. 17 is an elevational view of an asymmetrical article to be rolled by the dies of FIG. 14;

FIG. 18 is a side view of the article of FIG. 17;

FIG. 19A-19D are views similar to FIGS. 16A-16D but showing a further embodiment of the present invention;

FIG. 20 is an asymmetrical article to be rolled by the dies of FIGS. 19A and 19B;

FIG. 21 is a side view of the asymmetrical article of FIG. 20;

FIGS. 22A and 22B are sectional views of a pair of flat dies for rolling the article of FIGS. 20 and 21;

FIGS. 23A and 23B are schematic views of a pair of flat dies according to a further embodiment of the present invention;

FIG. 24A is a developed view of the die face of one of the dies of FIGS. 23A and 23B;

FIG. 24B is a sectional view taken along the line 24B—24B of FIG. 24A;

FIG. 24C is an elevational view of variously shaped workpieces obtained at each stages a—a, b—b, c—c, d—d of FIG. 24B;

FIG. 24D is a side view of the workpieces of FIG. 24C;

FIG. 25 is an elevational view of an asymmetrical article to be rolled by the dies of FIGS. 23A and 23B; and

FIG. 26 is a side view of the article of FIG. 25.

DETAILED DESCRIPTION OF THE PREFERRED EMBODIMENTS

FIGS. 1 and 2 show a pair of cylindrical dies 3, 4 according to an embodiment of the present invention. The dies 3, 4 are adapted so as to be capable of rolling an asymmetrical product or article P as shown in FIGS. 7 and 8. The article P is in the form of a stepped shaft having a pair of smaller diameter sections S₁, S₁ and a larger diameter section S₂ interposed therebetween. While the shaft sections S₁, S₂ are all arranged concentric, the larger diameter section S₂ has a pair of axially spaced projections G, G which are arranged asymmetric about the axis of the article P.

As seen from FIG. 1, the dies 3, 4 have substantially the same shape except for the number and position of grooves or depressions and adapted to be driven by an unshown driving means. Referring to FIGS. 2A and 2B, the die face 4a of the die 4 has a pair of first working sections 4c, 4c in the form of ridges spaced in the width direction of the die 4. The first working sections 4c, 4c each have biting ends 4b, 4b biting into a workpiece W at the beginning of rolling for forming the smaller diameter sections S₁, S₁ of the article P. The die face 4a also has a second working section 4d between the first working sections 4c, 4c for forming the larger diameter section S₂ of the article P.

As seen from FIGS. 2B and 2C, rolling of the workpiece W which is originally a straight round bar of the diameter d₀ begins as the process advances from the stage a—a to the stage b—b. In response to this, the opposite ends of the workpiece W start reducing in diameter by the effect of the first working sections 4c, 4c and formed into the smaller diameter sections S₁, S₁ of the diameter d₃. At the stage transiting from b—b to d—d, the central portion of the workpiece W reduces in diameter from d₀ to d₁ and then d₁ to d₂ and formed into the larger diameter section S₂ by the effect of the second working section 4d which is provided with a predetermined inclination in the place corresponding to the stage transiting from b—b to d—d.

The second working section 4d is formed with plural pairs of depressions 5, 6, 7 for forming the radial depressions G, G of the article P, each pair of which depressions are spaced from each other in the width direction of the die 4 by the amount corresponding to the distance between the projections G, G. The depressions 5, 6, 7 are arranged in a line at the same intervals, i.e., at an equal pitch in the longitudinal direction of the die 4. The pitch of the depressions 5, 6, 7 is set substantially equal to the distance over which the workpiece W rolls by one revolution, i.e., the circumference of the workpiece W so that an excess metal of the workpiece W is caused to flow progressively into the depressions 5, 6, 7 and formed into the radial projections G, G as shown in FIGS. 7 and 8.

Referring to FIGS. 3A to 3E, the rolling process by using the dies 3, 4 of this invention will be described more in detail hereinafter. The die 3 is substantially similar to the die 4 except for depressions 8, 9. The depressions 8, 9 are formed so as to be equal in pitch to the depressions 5, 6, 7 but differ from same in position relative to the workpiece W by the distance over which the workpiece W rolls by about half revolution, i.e.,

differ from the depressions 5, 6, 7 in phase by the amount corresponding to about half revolution of the workpiece W so that any one of the depressions 8, 9 of one die 4 and any one of the depressions 5, 6, 7 of the other die 3 do not come in contact with the workpiece W at the same time.

In FIG. 3A, a particular part-circular peripheral portion of the workpiece W is shown as being coming in contact with the depression 5. An excess metal of the workpiece W resulting from the reduction in diameter of the central portion thereof is thus caused to flow into the depression 5 and formed into a radial projection G as shown in FIG. 3B. As the rolling process advances further, the projection G having been formed by the depression 5 comes in engagement with the depression 8 as shown in FIG. 3C so that another excess metal of the workpiece W is introduced into the depression 8 to develop the projection G. In like manner, the projection G sequentially comes in engagement with the depressions 6, 9, 7 every half revolution of the workpiece W so as to develop the projection G further as shown in FIG. 3D. Finally, as shown in FIG. 3E, the projection G is finished by the depression 7, thereby completing the rolling process of the asymmetrical article P. By the rolling process mentioned above, the asymmetrical article P shown in FIGS. 7 and 8 can be obtained.

By the experiments conducted by the applicant, it was found desirable to set the pitch l of the depressions 5, 6, 7 or the depressions 8, 9 at a value about 1.0–1.2 times as large as the distance over which the workpiece W rolls by one revolution (i.e. the circumference of the workpiece W) since there is some slippage between the dies 3, 4 and the workpiece W during rolling, though the desirable pitch l also varies a little depending upon the shape of the article P to be rolled.

In the foregoing, it will be understood that the number of the depressions is not limitative but may be increased in order to form a larger projection. It will be further understood that three cylindrical dies may be employed to carry out the foregoing rolling process of this invention. In such a case, the depressions of each die are arranged to differ from each other in phase by the amount corresponding to about $\frac{1}{3}$ revolution of the workpiece or differ from each other in position relative to the workpiece by the distance over which the workpiece rolls by $\frac{1}{3}$ revolution. It will be further understood that the depressions may be designed so as to increase in volume progressively as exemplarily shown in FIG. 4 with respect to the depressions 5, 6 or on the contrary the depressions may be designed so as to reduce in volume progressively as exemplarily shown in FIG. 5.

FIG. 6 shows another embodiment in which a pair of flat dies 1, 2 are used for carrying out the foregoing rolling process of this invention in place of the cylindrical dies 3, 4.

FIGS. 9A to 9D show a method of forming a crank-shaft P₁ according to a further embodiment of the present invention.

In this embodiment, a workpiece W₁ is originally in the form of a straight round bar as shown in FIG. 9A and formed into an intermediate product shown in FIG. 9B by a single preliminary forming process.

The intermediate product W₁ is asymmetrical about its axis and includes a plurality of symmetrical or concentric shaft sections S₁, S₁ and a plurality of asymmetrical or eccentric shaft sections S₂, S₂. The shaft sections S₁, S₂ are arranged in compliance with the finished shape of the crankshaft or finished product P₁ shown in

FIG. 9D so that the intermediate product W_1 is ready to be forged. The preliminary forming of FIG. 9B is carried out by a rolling process using a pair of cylindrical dies 13, according to the present invention. The dies 13, as shown in FIGS. 10-12 and 13A-13D, are respectively formed with die faces 13a, 14a including first working sections 13c, 14c for forming the symmetrical or concentric shaft sections S_1 and second working sections 13d, 14d for forming asymmetrical or eccentric shaft sections S_2 having radial projections G.

By this rolling process, a prior art bending process can be dispensed with, which bending process has been indispensable for forming the asymmetrical or eccentric shaft sections S_2 in addition to a prior art rolling process.

Subsequently to the preliminary forming process of FIG. 9B, a forging process of FIG. 9C is performed twice, i.e., one for roughing and one for finishing. In this forging process, an excess metal portion or flange F is inevitably formed similarly to the prior art. However, since the workpiece W_1 can be formed into the shape of FIG. 9B more efficiently than before by the rolling process of this invention, the metal flow occurring in the subsequent forging process becomes more efficient and desirable than before, whereby to make it possible to reduce the volume of the excess metal portion F. After the forging process of FIG. 9C, the excess metal portion F is removed by a trimming process of FIG. 9D, whereby the workpiece W_1 is formed into the finished shape of the crankshaft P_1 .

By this embodiment, the manufacturing expense of the crankshaft can be reduced considerably since the bending process otherwise necessitated can be dispensed with. Further, by this embodiment, it becomes possible to employ a straight round bar as a workpiece for producing a crankshaft. This is effective for reducing the volume of the excess metal portion to be trimmed.

FIGS. 14 and 15 show a further embodiment in which a pair of cylindrical dies 23, 24 are used for rolling an asymmetrical product or article P_2 shown in FIGS. 17 and 18.

FIG. 16A is a developed view of the face 24a of the die 24, and FIG. 16B is a sectional view taken along the line 16B-16B of FIG. 16A. The die face 24a has a pair of first working sections 24c, 24c each having biting ends 24b, 24b and adapted for forming the symmetrical or concentric smaller diameter sections S_1 and a second working section 24d located between the first working sections 24b, 24b and adapted for forming the asymmetrical or eccentric larger diameter section S_2 . The second working section 24d is formed with alternate depressions 25, 26, 27 and projections 28, 29, 30 in such a manner that the depressions 25, 26, 27 become deeper the remoter they are located from the biting ends 24b, 24b while on the other hand the projections 28, 29, 30 become higher the remoter they are located from the biting ends 24b, 24b. The above structure is substantially similar in case of the other die 23, and the die 23 is formed with alternate projections 31, 32, 33 and depressions 34, 35, 36.

FIG. 16C shows the shapes into which the workpiece W_2 is formed at each stages a—a, b—b, c—c, d—d. FIG. 16D shows in side elevation the workpiece W_2 at the stages a—a, b—b, c—c, d—d. As seen from FIGS. 16B and 16C, rolling of the workpiece W_2 begins as the process advances from the stage a—a to the stage b—b. In response to this, the opposite ends of the workpiece

W_2 start reducing in diameter by the effect of the first working sections 23c, 24c and formed into the smaller diameter shaft sections S_1 , S_1 of the diameter d_1 . Up to this stage, the workpiece W_2 is held symmetrical about its axis and the diameter d_0 of the larger diameter section S_2 is maintained unchanged.

Further, at the stage transiting from b—b to d—d via c—c, the diameter d_1 of the smaller diameter sections S_1 , S_1 is held unchanged since the first working sections 23c, 23c have no inclination. While the diameter d_0 of the larger diameter section S_2 is held unchanged for the similar reason, the eccentricity of the larger diameter section S_2 increases progressively.

As shown in FIG. 15, the pitch of the projections 28,

29, 30 of the die 24 and the pitch of the projections 31, 32, 33 of the die 23 are set at a value substantially equal to the distance over which the larger diameter section S_2 of the workpiece W_2 rolls by one revolution, i.e., the circumference of the larger diameter section or eccentric shaft section S_2 . Further, the projections 28, 29, 30 of the die 24 differ from the projections 31, 32, 33 of the die 23 in position relative to the workpiece W_2 by the distance over which the workpiece W_2 rolls by about half revolution, i.e., differ in phase from the projections 31, 32, 33 by the amount corresponding to about half revolution of the workpiece W_2 so that any one of the projections 28, 29, 30 and any one of the projections 31, 32, 33 do not come in contact with the workpiece W_2 at the same time.

Reference being made by way of example to the projection 29 of the die 24 which is matched with the depression 35 of the die 23 as shown in FIG. 15, the eccentricity of the larger diameter section S_2 relative to the smaller diameter sections S_1 , S_1 increases progressively during the time when the larger diameter section S_1 rolls along the upward slope 29a of the top face 29b of the projection 29 and maximized when the larger diameter section S_2 comes in contact with the upper most point 29c of the top face 29b. The above occurs similarly in case of the other projections 28, 30 and the projections 31, 32, 33. The larger diameter section S_2 is made eccentric in the above manner and constitutes the eccentric shaft section of the asymmetrical article P_2 shown in FIGS. 17 and 18.

FIGS. 19A-19D show a further embodiment whereby the rolling process of this invention is used for manufacturing an asymmetrical article P_3 shown in FIGS. 20 and 21. The article P_3 has an eccentric shaft section E and concentric shaft sections S_1 , all of which sections are of the same diameter. In this embodiment, since it is not necessary to change the diameter d_0 of the workpiece W_3 but the diameter of the finished product P_3 is equal to the diameter d_0 of the workpiece W_3 , the die faces 43a, 44a of the cylindrical dies 43, 44 are not provided with such first working sections as are provided in the previous embodiment of FIGS. 14-15 and 16A-16D.

FIGS. 22A and 22B show a further embodiment in which a pair of flat or straight dies 51, 52 are used for carrying out the same rolling process as the previous embodiment of FIGS. 19A-19D.

FIGS. 23A and 23B show a further embodiment wherein a pair of flat or straight dies 61, 62 are used for rolling an asymmetrical article P_4 shown in FIGS. 25 and 26.

FIG. 24A is a plan view of the die face 61a of the die 61, and FIG. 24B is a sectional view taken along the line 24B-24B of FIG. 24A. The die face 61a is formed with

a plurality of projections 63, 64 for forming the eccentric shaft sections S₁, S₁ of the asymmetrical article P₄. More specifically, the die face 61a consists of a generally planar surface section 61b and plural pairs of projections 63, 63 or 64, 64, each pair of which projections 63, 63 or 64, 64 are arranged so as to oppose in the width direction of the die 61 and symmetrically about the longitudinal center axis of the die 61. The other die 62 is substantially similar to the die 61 except that it is formed with a pair of projections 65, 65 only. The projections 63, 64, 65 have angled top faces 63b, 64b, 65b and are of the heights that vary in such a manner that the projections 65 is higher than the projection 63 and the projection 64 is higher than the projection 65. The projections 63, 64, 65 resemble each other in shape, and the angled top faces 63b, 64b, 65b are respectively provided with upward slopes 63c, 64c, 65c and downward slopes 63d, 64d, 65d in such a manner that the upward slopes are more gentle than the downward slopes.

FIG. 24C shows the shapes into which the workpiece W₄ is formed at the stages a—a, b—b, c—c of the rolling process shown in FIG. 24B and FIG. 24D shows in side elevation the workpiece W₄ at those stages. As seen from FIGS. 24B and 24C, rolling of the workpiece W₄ begins as the process advances from the stage a—a to the stage b—b whereby the opposite end portions of the workpiece W₄ which are to be formed into the eccentric sections S₁, S₁ are reduced in diameter to d₁ (d₀>d₁) while at the same time the axes of the opposite end portions are caused to become eccentric progressively. In this case, the diameter d₀ of the larger diameter section S₂ is maintained unchanged.

Further, as the process advances from the stage b—b to the stage c—c, the eccentric portions S₁, S₁ are further reduced in diameter to d₂ (d₁>d₂) by the effect of the projection 64, while at the same time the eccentricity of the eccentric portions S₁, S₁ are further increased so that the circumferential surface of the eccentric portions S₁, S₁ becomes in part flush with that of the larger diameter section S₂. In this stage, the diameter d₀ of the larger diameter section S₂ is still maintained unchanged.

As shown in FIGS. 23A and 23B, the pitch of the projections 63, 64 of the flat dies 61 are set at a value substantially equal to the distance over which the larger diameter section S₂ rolls by one revolution, i.e., equal to the circumference of the larger diameter section S₂, and the projection 65 is arranged so as to differ from the projections 63, 64 in phase by the amount corresponding to about half revolution of the workpiece W₄, i.e., so as to differ from the projections 63, 64 in position relative to the workpiece W₄ by the distance over which the workpiece W₄ rolls by about half revolution such that the projection 65 does not come in contact with the workpiece W₄ together with either of the projections 63, 64.

Accordingly, as shown in FIGS. 23A and 23B, the eccentricity of the eccentric shaft sections S₁, S₁ is increased as the workpiece W₄ rolls along the upward slopes of each projections. At the same time when the workpiece W₄ finishes rolling along the downward slope of the projection 63, it begins to roll along the upward slope of the projection 65. In this manner, the workpiece W₄ rolls from the projection 65 to the projection 64. The eccentricity of the eccentric shaft section S₁, S₁ is maximized when the eccentric shaft sections S₂, S₂ are brought into engagement with the upper most point of the top face of the projection 64, whereby the workpiece W₄ is formed into the asymmetrical arti-

cle P₄ shown in FIGS. 25 and 26. In the meantime, the reduction in diameter of the eccentric shaft sections S₁, S₁ and the eccentricity of same can be varied by varying the heights of the projections 63, 64, 65.

In this embodiment, by providing an inclination to the working sections 61b, 62b of the die faces 61a, 62a, the diameter d₀ of the larger diameter section S₂ can be changed. By making the pair of projections different from each other in height, the eccentric shaft sections S₁ can be made different in diameter from each other. Further, it will be understood that in place of the flat dies 61, 62 a pair of cylindrical dies may be used.

What is claimed is:

1. A method of forming an asymmetrical article by rolling, comprising:

preparing a circumferentially symmetrical article; preparing a plurality of dies between which said article is to be rolled as said dies are driven to move in opposite directions, said dies each having die faces which are formed with independent patterns arranged in lines extending only essentially in parallel to the directions of movement of said dies and which are capable of being sequentially brought into engagement with only a particular part-circular peripheral portion of the article as the article rolls between said die faces; and

compressing the article while driving the same to roll between said die faces by moving said dies in opposite directions and forming said particular portion of the article into a circumferentially asymmetrical portion of the article by the effect of said portions of said die faces.

2. A method as set forth in claim 1, wherein said step of preparing said dies comprises the step of preparing die faces in which each of said patterns has a pitch which is set substantially equal to a distance over which said article rolls during one revolution.

3. A method of forming an asymmetrical article by rolling, comprising:

preparing a circumferentially symmetrical article; preparing a plurality of dies between which said article is to be rolled as said dies are driven to move in opposite directions, said dies each having die faces which are formed with depressions arranged in lines extending only essentially in parallel to the directions of movement of said dies and which are capable of being sequentially brought into engagement with only a particular part-circular peripheral portion of the article as the article rolls between said die faces; and

compressing the article while driving the same to roll between said die faces by moving said dies in opposite directions and allowing an excess metal of the article to flow into said depressions sequentially, thereby forming a circumferentially asymmetrical part of the article.

4. A method as set forth in claim 3, wherein said step of preparing said dies comprises the step of preparing die faces in which said depressions formed in each die face have a pitch which is set substantially equal to a distance over which said article rolls during one revolution.

5. A method of forming a crankshaft comprising: preparing a workpiece in the form of a straight round bar;

preparing a plurality of dies between which the workpiece is to be rolled as said dies are driven to move in opposite directions, said dies each having

die faces which are formed with independent patterns arranged in lines extending in the directions of movement of said dies and which are capable of being sequentially brought into engagement with only a particular part-circular peripheral portion of the workpiece as the workpiece rolls between said die faces;

compressing the workpiece while driving the same to roll between said die faces, thereby preliminarily forming the workpiece into an intermediate product which is asymmetrical about its axis and resembles in shape to a crankshaft;

allowing the intermediate product to be forged, thereby forming the same into a semifinished shape having an excess metal flange; and

trimming the excess metal flange, thereby forming the workpiece into said crankshaft.

6. A method as set forth in claim 5 wherein said forging comprises forging of roughing type and forging of finishing type.

7. A method of forming an asymmetrical article by rolling, comprising:

preparing a circumferentially symmetrical article;

preparing a plurality of dies between which said article is to be rolled as said dies are driven to move in opposite directions, said dies each having die faces which are formed with alternate depressions and projections arranged in lines extending only essentially in parallel to the directions of movement of said dies and which are capable of being sequentially brought into engagement with a particular part-circular peripheral portion of the article; and compressing the article while driving the same to roll between said die faces by moving said dies in opposite directions and allowing said particular portion of the article to become eccentric progressively by the effect of said depressions and projections.

8. A method as set forth in claim 7, wherein said step of preparing said dies comprises the step of preparing die faces in which said depressions and projections formed in each die face have pitches which are set substantially equal to a distance over which said article rolls during one revolution.

9. A method of forming an asymmetrical article by rolling, comprising:

preparing a circumferentially symmetrical article

preparing a plurality of dies between which said article is to be rolled as said dies are driven to move in opposite directions, said dies each having die faces which are formed with projections arranged in lines extending only essentially in parallel to the directions of movement of said dies and which are capable of being sequentially brought into engagement with particular part-circular portions of the article, respectively as the article rolls between said die faces; and

compressing the article while driving the same to roll between said die faces by moving said dies in opposite directions and allowing said particular portions of the article to become eccentric progressively by the effect of said projections.

10. A method as set forth in claim 9, wherein said step of preparing said dies comprises the step of preparing die faces in which said projections formed in each die face have a pitch which is set substantially equal to a distance over which said article rolls during one revolution.

11. A method of forming an asymmetrical article by rolling, comprising:

preparing a circumferentially symmetrical article; preparing a pair of first and second dies between which said article is to be rolled as said dies are driven to move in opposite directions, said dies each having die faces which are formed with projections which are arranged in lines extending only essentially in parallel to the directions of movement of said dies and which are capable of being sequentially brought into engagement with a particular circular peripheral portion of the article as the article rolls between said die faces;

compressing the article while driving the same to roll between said die faces by moving said dies in opposite directions and allowing said particular portion of the article to become eccentric progressively by the effect of said projections; and

said projections increasing in height as the rolling process advances.

12. A method as set forth in claim 11, wherein said step of preparing said dies comprises the step of preparing die faces in which said projections formed in each die face have a pitch which is set substantially equal to a distance over which said article rolls during one revolution.

13. A method of forming an asymmetrical article by rolling, comprising:

preparing a circumferentially symmetrical article; preparing a plurality of dies between which said article is to be rolled as said dies are driven to move in opposite directions, said dies each having die faces which are formed with independent patterns, each of which is arranged in a line extending only essentially in parallel to the directions of movement of said dies and which has a pitch which is set substantially equal to a distance over which said article rolls during one revolution; and

compressing the article while driving the same to roll between said die faces by moving said dies in opposite direction; and

forming said particular portion of the article into a circumferentially asymmetrical portion of the article sequentially engaging said particular portion with said patterns of said die faces.
